UNITED STATES PATENT OFFICE.

GEORGE W. PIGGOTT, OF NEW YORK, N. Y., ASSIGNOR TO THE HARTFORD CARPET COMPANY, OF HARTFORD, CONNECTICUT.

DESIGN FOR A CARPET.

Specification forming part of Design No. **11,089**, dated March 25, 1879; application filed February 24, 1879.

[Term of patent 3½ years.]

To all whom it may concern:

Be it known that I, GEORGE W. PIGGOTT, of the city of New York, county and State of New York, have invented a new and original Design for Carpets, of which the following is a specification.

This invention relates to a new and original design for carpets, oil-cloths, and similar fabrics.

It consists of the new ornamentation and arrangement of parts constituting the design hereinafter more fully pointed out.

The accompanying photographic illustration represents a face view of my newly-designed carpet.

The design consists more particularly of a number of irregular figures, hereinafter specified, which are arranged, as is shown in the photographic illustration, to form one complete harmonious design.

In the illustration, the letter *a* represents a curved, approximately oval-shaped figure. At its side is a semicircular figure, *b*, (its upper end is seen at the bottom of the photograph,) partly surrounded by a border and in part overlapped by the figure *a*. At the side of the figure *a* is also a small square, *d*, and an irregular figure, *e*, having four straight and three concave sides.

f is another irregular figure, one of its sides having a step-shaped outline, another side is arc-shaped, while its remaining sides are formed of straight lines.

Above the figure *f* is a smaller figure, *g*, which is formed of two concentric arcs and of two short straight sides, and which has a small downward projection that partly overlaps the figure *b*.

h is a figure with partly straight and partly curved outline.

Below the figures *f* *h* is a figure, *i*, having two triangular projections. The figure *i* partly incloses a figure, *k*, partly surrounded by bor-

der, and having a downward projection, which is formed of one concave and one convex side.

l is a right-angled-triangular figure with irregularly-curved hypotenuse.

m is a curvilinear figure wedged in between the figures *i*, *k*, *l*, and *n*. Said figure *n* is formed of one curved, two straight, and one zigzag side.

The several figures constituting the above design are severally richly ornamented by the representation of flowers, scrolls, and other embellishments.

I claim as my invention—

1. The design for a carpet, consisting of the figures *a b d*, substantially as shown.
2. The design for a carpet, consisting of the figure *e*, which has four straight and three concave sides, substantially as shown.
3. The design for a carpet, consisting of the figure *f*, which is formed by a step-shaped line on one side and by an arc and straight lines on the others, substantially as shown.
4. The design for a carpet, consisting of the figures *f g*, substantially as shown.
5. The design for a carpet, consisting of the figures *h i*, substantially as shown.
6. The design for a carpet, consisting of the figures *i k*, the figure *i* having two triangular projections, and partly inclosing the figure *k*, substantially as shown.
7. The design for a carpet, consisting of the figures *k l m*, substantially as shown.
8. The design for a carpet, consisting of the figure *n*, that has one curved, two straight, and one zigzag side, substantially as shown.
9. The design for a carpet, consisting of the figures *a b d e f g h i k l m*, and *n*, substantially as shown.

GEORGE W. PIGGOTT.
